UNITED STATES PATENT OFFICE

90,680

DESIGN FOR A RADIOCABINET

Milton C. Rosenow, Wilmette, and Albert L. Jenks, Chicago, Ill., assignors to Grigsby-Grunow Company, Chicago, Ill., a corporation of Illinois

Application May 8, 1933. Serial No. 48,048

Term of patent 7 years

To all whom it may concern:

Be it known that MILTON C. ROSENOW and ALBERT L. JENKS, citizens of the United States of America, residing at Wilmette and Chicago, respectively, in the county of Cook and State of Illinois, have invented a new, original, and ornamental Design for Radiocabinets, of which the following is a specification, reference being had to the accompanying drawing, forming part thereof.

The figure is a perspective view of the cabinet.

I claim:

The ornamental design for a radiocabinet as shown.

MILTON C. ROSENOW.
ALBERT L. JENKS.
